JACOB SUTER AND WENZEL LENK, OF JERSEY CITY, NEW JERSEY.

SELF-PLAYING MUSICAL INSTRUMENT.

SPECIFICATION forming part of Letters Patent No. 747,802, dated December 22, 1903.

Application filed February 3, 1903. Serial No. 141,650. (No model.)

To all whom it may concern:

Be it known that we, JACOB SUTER and WENZEL LENK, both citizens of the United States, and residents of Jersey City, in the county of Hudson and State of New Jersey, have invented a new and Improved Self-Playing Musical Instrument, of which the following is a full, clear, and exact description.

The invention relates to musical instruments of the zithern type; and its object is to provide a new and improved self-playing musical instrument arranged to pick the strings, actuate bells or other sounding devices, and to insure a proper gradation of the tones according to the requirements of the music produced and indicated on the note-sheet.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a plan view of the improvement. Fig. 2 is an enlarged cross-section of part of the same on the line 2 2 of Fig. 1. Fig. 3 is a plan view of the same. Fig. 4 is an enlarged longitudinal sectional elevation of the improvement on the line 4 4 of Fig. 1. Fig. 5 is an enlarged cross-section of a plurality of strings and their dampers and pickers in different positions. Fig. 6 is an enlarged cross-section of the gradation device on the line 6 6 of Fig. 7. Fig. 7 is a cross-section of the same on the line 7 7 of Fig. 6. Fig. 8 is a plan view of the same; and Fig. 9 is an enlarged side elevation of the improvement, part of the note-sheet being broken out.

The body A of the musical instrument is of suitable construction and carries sounding devices, such as strings B and bells C, for instance, the said bells being preferably rested on a bracket C', attached to the body A. The strings B are stretched in the usual manner over the sounding-board, and the said strings and the bells C are adapted to be engaged by sounders D and E, respectively, of which the sounders D are in the shape of pickers for picking the strings and the sounders E are

in the form of strikers or hammers for striking the bells C. Both sets of sounders D and E are controlled from a note-sheet F, preferably in the form of an endless band having apertures representing the notes of the piece of music to be played by the instrument. 55

Each sounder d has a sounder-lever D' extending in the direction of the length of its string and fulcrumed on a transverse rod D², carried by the body A, so that the lever can swing up and down. The sounder-lever D' is made of spring metal to allow it to swing sidewise by its own resiliency to move into operative position when released or into a non-operative position, as hereinafter more fully explained. On the forward free end of each sounder-lever D' is arranged a depending arm D⁴, carrying a transversely-extending picker D⁵ in the shape of a lug for picking the string in an upward direction, the said arm D⁴ normally standing to one side of the string and spaced therefrom, with the picker a distance below the string, as plainly indicated in Fig. 5. 70

On the face of the arm D⁴, next to its string B, is a piece of felt or other material forming a damper D⁶ for damping the string immediately previous to the picker D⁵ rising and 80 picking the string.

Each sounder-lever D' is connected by a link G with a note-sheet lever H, fulcrumed on a frame I, attached to the body A, and the said lever rests with its free end H' on the note-sheet to hold the sounder-lever D' against the tension of its spring in a normal position—that is, with the picking-arm D⁴ and the picker D⁵ a distance from the corresponding string. Now when the note-sheet travels 85 and the free end H' of the note-sheet lever H drops into a note-sheet aperture then the sounder-lever D' is released and swings by its own resiliency into an operative position—that is, the damper D⁶ moves into engagement 95 with the side of the string and damps the same—and the picker D⁵ is now immediately below the string, so that on now swinging the sounder-lever upward the string is picked. As soon as the string has been picked the aperture in the traveling note-sheet leaves the free end of the note-sheet lever H, and the latter is thereby returned to its normal position, whereby a pull is exerted by the link G 100

on the sounder-lever D' to swing the same back against the tension of its spring, and thereby swing the picker D⁵ and its arm D⁴ away from the string. The sounder-lever 5 now swings downward to its normal position by its own weight or by the action of a spring.

In order to impart an upward swinging picking motion to the sounder-levers as described, the following device is provided: A 10 continually-rotatable shaft J, journaled in suitable bearings, extends transversely over the strings B and carries a plurality of star-wheels K, one for each picking-lever D', and each of the latter is provided on the side adjacent to its star-wheel with a pin or friction-roller D⁷, normally out of engagement with the arms of the star-wheel—that is, as long as the sounder-lever is in a normal position. Now when a sounder-lever D' is released, as 15 above described, and moves into damping position then the friction-roller D⁷ engages an arm of the rotating star-wheel K and is carried upward by the latter, thus imparting an upward-swinging motion to the sounder-lever for the picker D⁵ to pick the string, and when this is done the sounder-lever D' is pulled back, as mentioned, to disengage the friction-roller D⁷ from the star-wheel K. The sounder-lever now drops downward to its normal position by its own weight or by the action of a spring, as previously mentioned.

The strikers or hammers forming the sounders E for the bells C are secured on the free ends of sounder-levers D⁸, similar to the 35 sounder-levers D', and likewise connected by links G' with note-sheet levers H², arranged alongside the levers H, and likewise actuated by the note-sheet, the same as the levers H. Each of the sounder-levers D⁸ is provided 40 with a friction-roller D⁹ for engagement by a star-wheel K', secured on the shaft J, previously mentioned.

Now when the music calls for the sounding of a bell the corresponding aperture in 45 the note-sheet registers with the lever H², so that the sounder-lever D⁸ of this lever is released, and consequently the sounder-lever D⁸ swings into an operative position—that is, its friction-roller engages the corresponding 50 star-wheel K' for the latter to impart an upward swinging motion to the sounder-lever D⁸. When this has been done, the note-sheet by having its aperture leave the lever H² draws the sounder-lever D⁸ back out of engagement with the star-wheel K', so that the sounder-lever now swings downward by its own weight and in doing so the sounder E sounds the corresponding bell.

Each of the levers D' and D⁸ has its rear 60 end D⁹ abutting against a felted stop-rail L, carried by the body A, to limit the downward swinging motion of the said levers.

The shaft J receives a continuous rotary motion from a motor N, which also imparts 65 a traveling motion to the note-sheet F, the said motor N being of any approved construction. As shown, the shaft J has a frictional

gearing connection with the motor—that is, the shaft J carries a friction-wheel J', in mesh with a friction-wheel N', driven by the motor. 70

A shaft N², driven by the motor N, is provided at its upper end with a bevel gear-wheel N³, in mesh with a pinion O'; secured on a shaft O², carrying a drum O, provided at its sides with toothed wheels O³ for engaging spaced apertures F², formed on the sides of the note-sheet F, so that when the drum O is rotated a traveling motion is given to the note-sheet F to bring the apertures F² therein in register with the free ends of the levers H and H², as previously explained. 75

The note-sheet F in passing to the drum O passes between a rod I', held on the frame I, and a roller I², journaled in a cross-bar I³ hinged at one end on the frame I and adapted to be locked in place therein by a hook I⁴, engaging the free end of the cross-bar. (See Figs. 4 and 9.) By swinging the hook I⁴ upward the cross-bar I³ may be readily swung away from the note-sheet to allow of convenient removal of the note-sheet and the placing of another in position on the drum. Below the roller I² is arranged a second roller I⁵, likewise journaled in the cross-bar I³, and the said cross-bar and rollers I² and I⁵ are so located that the ends H' of the lever H engage the note-sheet below the rod I', and as the rollers I² and I⁵ are on the opposite or outer face of the sheet it is evident that the note-sheet is not bent outward by the ends 100 H' of the levers H, which are under tension by the action of the spring sounder-levers D' and D⁸, which tend to press the ends H' against the inner face of the note-sheet. 90

In order to produce the desired gradation 105 of tones as called for by the piece of music, the following device is provided, (see Figs. 1, 6, 7, and 8:) A slide Q is mounted to slide in suitable bearings and extends transversely over the strings, and on the said slide Q are 110 secured upwardly-extending arms Q', one for each sounder-lever D', to allow the latter to swing a desired distance when released, so that the picker picks the string with more or less force according to the position of the arm 115 Q' at the time. On one end of the slide Q is secured an upwardly-extending lug or pin Q², projecting into an angular slot R', formed on the hub R² of a double arm R, pivotally connected at its free ends with upwardly-extending links T T', having lugs T² and T³, respectively, adapted to be alternately engaged by a pin U', held in a loop U², formed on the free end of a spring-lever U, similar to the lever D', and likewise connected by a 120 link G² with a note-sheet lever H³. The pin U' extends to one side of the loop U² to move into engagement with a star-wheel K², secured on the shaft J, and hence when the lever H³ is allowed to drop by a corresponding 125 aperture in the note-sheet registering with the said lever then the lever U is released and its pin U' moves in engagement with the star-wheel K². As the latter rotates it im- 130

parts an upward swinging motion to the lever U, and consequently the pin U' engages the lug T² or T³, then in a lowermost position, to impart an upward movement to the corresponding lug and its link T or T' to rock the arm R, so that the slot R' acts on the pin Q² to slide the slide Q transversely across the strings, so that the arms Q' move nearer to or farther from the sounder-levers D', thus limiting the swinging motion of the said levers when released, and consequently causing the pickers D⁵ to pick the strings with more or less force.

By the arrangement described any desired gradation—such as piano, pianissimo, forte, fortissimo—can be obtained, it being understood, however, that the lever H³ is controlled by a separate row of apertures in the note-sheet F, and the said apertures are of different lengths according to the gradation desired, so that the spring-lever U is caused to swing upward a distance more or less according to the length of time the lever is held in a released position. It is understood that if the lever U is released but for an instant the star-wheel K² can lift the lever but a short distance; but in case a long aperture is in register with the lever H³ then the lever U is released for a longer period, and consequently this lever is lifted higher and the slide is shifted a longer distance. It is further understood that the double arm R remains in the position to which it is moved until the next release of the lever U, so that the instrument plays at a certain gradation until the slide Q is again shifted. When the link T is moved upward by the pin U' of the lever U, then the slide Q is shifted to bring the arms Q' nearer to the sounder-levers D'—that is, to produce a piano or pianissimo tone—and when the other link T' is moved upward the slide Q is moved in the reverse direction to allow the levers D to swing farther over for the pickers D⁵ to fully pick the strings and produce forte or fortissimo tones.

When the note-sheet F is placed in position on the drum O, then the body of the note-sheet acts on all the levers H, H², and H³ to impart a swinging motion to the same to pull on the sounder-levers D', D⁸, and U and swing the same sidewise under tension. The motor when started imparts a traveling motion to the note-sheet F, and as soon as one of its apertures F' comes in register with the free end of a lever H, H², or H³ then the corresponding sounder-lever D', D⁸, or U is released, and this lever now swings sidewise into operative position to be subsequently swung upward by the corresponding star-wheel K, K', or K² for the purpose fully described above. Thus when a sounder-lever D' is acted on it sounds its corresponding string, and when a sounder-lever D⁸ is allowed to drop it sounds its bell, and the lever U causes a shifting of the slide Q to vary the gradation of the tones.

The note-sheet F is firmly stretched between the drum O and the rod I' and rollers I² and I³, and the free ends H' of the levers H, H², and H³ engage the note-sheet at the 70 said stretched portion.

The connection between the links G, G', and G² and their levers D', D⁸, and U, respectively is preferably adjustable to allow of adjusting the said levers relative to the note-sheet levers H, H², and H³ to bring the latter in correct position to the note-sheet and the pickers in proper relation to the strings and star-wheels.

Having thus described our invention, we 80 claim as new and desire to secure by Letters Patent—

1. A self-playing musical instrument having sounding devices, spring-actuating levers for sounding the sounding devices, the said actuating-levers being mounted to swing up and down on their fulcrum and free to swing sideways owing to their resiliency, note-sheet levers connected with the actuating-levers, a note-sheet controlling said note-sheet levers 90 to normally hold the actuating-levers out of operative position relative to the sounding devices, and to release the same when a desired tone is to be produced, and continuously-revolving means for engaging the actuating-levers when released to move the said levers in engagement with the sounding devices, to sound the same, as set forth.

2. A self-playing musical instrument provided with sounding devices, means for sounding the sounding devices including resilient sounder-levers, a note-sheet normally holding said means with the sounder-levers out of operative position relative to the sounding devices, the said note-sheet being constructed 105 to release the said sounding means to permit the sounder-levers to move by their resiliency into operative position, and revolving star-wheels for engagement by the said levers to actuate the levers and thereby sound the 110 sounding devices, as set forth.

3. A self-playing musical instrument provided with sounding devices, means for sounding the sounding devices including sounder-levers, a note-sheet for normally holding said means with the sounder-levers out of engagement with the sounding devices, the note-sheet having apertures for releasing the said means, revolving mechanism for engagement by the sounder-levers when released to actuate the latter and thereby sound the sounding devices and a tone-gradation device comprising a slide provided with arms one for each sounder-lever, the said slide being controlled from the note-sheet, as set forth.

4. A self-playing musical instrument, comprising sounding devices, sounder-levers provided with means for sounding the sounder devices, means for actuating the sounder-levers, a tone-gradation device comprising a 130 slide provided with arms one for each sounder-lever, and means for actuating the slide to

move the arms toward or from the sounder-levers to limit the movement of the latter as set forth.

5. A self-playing musical instrument, comprising sounding devices, sounder-levers for the same mounted to move up and down on their fulcrum and having springs for moving the levers sidewise into operative position relative to the sounding devices, means for actuating the sounder-levers when passing into operative position to sound the sounding devices, a note-sheet, and note-sheet levers connected with the sounder-levers, the note-sheet normally holding the sounder-levers against the tension of their springs and out of operative position, the note-sheet having means for releasing the note-sheet levers to permit the sounder-levers to move into operative position, as set forth.
- 20 6. A self-playing musical instrument, having sounding devices, spring sounder-levers for the same mounted to swing up and down on their fulcrum and free to swing sidewise owing to their resiliency, means for holding the said levers, normally out of operative position relative to the sounding devices, and continuously-revolving wheels, for engaging the sounder-levers, to actuate the same when released, as set forth.
- 25 7. A self-playing musical instrument, having sounding devices, spring sounder-levers for the same mounted to swing up and down on their fulcrum and free to swing sidewise owing to their resiliency, levers engaging a note-sheet, and connected with the sounder-levers for holding the same normally out of operative position relative to the sounding devices and for releasing a sounder-lever when a desired tone is to be produced, and
- 30 actuating means for the said sounder-levers, to actuate the latter when released, the said actuating means comprising a continuously-revolving shaft, star-wheels secured thereon, one for each sounding device, the sounder-levers having projections for engagement with the arms of the star-wheels, as set forth.
- 35 8. A self-playing musical instrument, having strings, spring-pressed levers having pickers for picking the strings, normally out of operative position relative to the strings, and continuously-revolving star-wheels, adapted to be engaged by projections on the said levers when the latter are released to actuate the levers, for their pickers to pick the strings, as set forth.
- 40 9. A self-playing musical instrument, having strings, spring-pressed levers having pickers for picking the strings, normally out of operative position relative to the strings, continuously-revolving star-wheels, adapted to be engaged by projections on the said levers when the latter are released to actuate the levers, for their pickers to pick the strings,
- 45 note-sheet recesses registering with the levers, said levers being normally held against

release by the note-sheet body, and links connecting the note-sheet levers with the spring-pressed sounding-levers, as set forth.

10. A self-playing musical instrument, having strings, spring-pressed levers having pickers for picking the strings, normally out of operative position relative to the strings, continuously-revolving star-wheels, adapted to be engaged by projections on the said levers when the latter are released to actuate the levers, for their pickers to pick the strings, and a tone-gradation device for shifting the said spring-pressed levers, controlled by the note-sheet, the tone-gradation device being actuated by one of the star-wheels, as set forth.

11. A self-playing musical instrument having a tone-gradation device, comprising a slide having connection with the sounders for the sounding devices, means on the slide for sliding it in either direction, a revoluble star-wheel and intermediate mechanism, for actuating the said means, as set forth.

12. A self-playing musical instrument having a tone-gradation device, comprising a slide having connection with the sounders for the sounding device, means for sliding the slide in either direction, a lever controlled by a note-sheet, for moving the said means into operative position, and a revoluble star-wheel for actuating the said means, to impart motion to the slide, as set forth.

13. A self-playing musical instrument having a tone-gradation device, comprising a slide having arms for engaging the sounders for the sounding device, a double arm mounted on the slide and arranged to move the slide in either direction, links extending from the double arm and having lugs, a lever controlled by a note-sheet and carrying a pin for alternately engaging the lugs on the said links, and a star-wheel for engaging the said lever, to lift the latter and with it the arm carried at the time, as set forth.

14. A self-playing musical instrument provided with note-sheet levers engaged by a note-sheet, spring-sounder levers mounted to swing up and down on their fulcrum and free to swing sidewise, owing to their resiliency, a link between a sounder-lever and the corresponding note-sheet lever, to release the sounder-lever and to allow the same to move into an operative position on the corresponding note-sheet lever being actuated by the note-sheet, a sounder held on each sounder-lever, for actuating the sounding device, and a revoluble star-wheel, for engaging the sounder-lever, to impart a swinging motion to the lever, to cause the sounders to sound the sounding device, as set forth.

15. A self-playing musical instrument having strings and bells, levers having pickers for picking the strings, levers having hammers for striking the bells, a note-sheet, levers connected with the picker-levers and the hammer-levers and controlled by the note-

sheet to normally hold the picker and hammer levers out of operative position, and to release the same when a desired tone is to be produced, means for actuating the said picker and hammer levers when in operative position, and a tone-gradation device for the picker-levers and controlled from the note-sheet, the said gradation device comprising a slide extending transversely over the strings, and provided with arms one for each picker-lever, means for sliding the slide in either

direction, and mechanism for actuating the said means, as set forth.

In testimony whereof we have signed our names to this specification in the presence of 15 two subscribing witnesses.
